UNITED STATES PATENT OFFICE.

LORENZO PIGNANI AND FRANK PIGNANI, OF DILLTOWN, PENNSYLVANIA.

CAR COUPLING.

1,403,193.

Specification of Letters Patent. Patented Jan. 10, 1922.

Application filed September 29, 1919. Serial No. 327,184.

To all whom it may concern:

Be it known that we, LORENZO PIGNANI, a subject of the King of Italy, and FRANK PIGNANI, a citizen of the United States, and residents of Dilltown, in the county of Indiana and State of Pennsylvania, have invented certain new and useful Improvements in Car Couplings, of which the following is a specification.

10 Our invention relates to car couplings, and particularly to the automatically operated car couplings of the link and pin type.

15 The purpose of our invention is to provide a car coupling of the above described character which is particularly, although not necessarily, adapted for use on mine cars, the coupling containing the desirable features of simplicity, durability, efficiency, and constructed to make and maintain the coupling at all times and under most difficult conditions.

20 We will describe one form of car coupling embodying our invention and will then point out the novel features in claims.

25 In the accompanying drawings:

Figures 1 and 2 are fragmentary views of the ends of a pair of adjacent mine cars having applied thereto one form of car coupling embodying our invention;

30 Figures 3 and 4 are vertical sectional views of the two parts of the coupling shown in Figures 1 and 2;

Figure 5 is a plan view partly in section showing the coupling member shown in Figure 3;

Figures 6 and 7 are enlarged detail views of the coupling member shown in Figure 5.

Similar reference characters refer to similar parts in each of the several views.

40 Referring specifically to the drawings, and particularly to Figures 1 and 2, M and M' designate mine cars of the usual construction having secured to the under sides thereof draw bars B and B', respectively, which project beyond the confronting ends of the cars and have arranged upon these projecting ends the parts C and C', which constitute the subject-matter of our invention. The parts C and C' comprise draw heads H and H', respectively, formed with extensions L and L' which are secured to the respective draw bars B and B' by means of bolts 15. Each draw head H or H' is provided with a compartment 16 or 16', the upper and lower walls of which converge toward the inner ends of a second compartment 17 or 17',

which constitutes the mouth of the draw head. As shown in Figure 5, the mouth 17 or 17' is of substantially rectangular formation and is provided with inwardly inclined 60 walls.

At the juncture of the compartments 16 and 17, the upper and lower walls of the draw head H are provided with registering openings, the lower one 18 of which is circular to receive a coupling pin P. The upper opening communicates with a housing A comprising front and rear walls 19 and 20, respectively, a bottom wall 21, and a cover plate 21a. The inner face of each wall 19 70 and 20 is provided with narrow grooves 23 between which is formed a relatively wide groove 24.

Working vertically within the housing A is a coupling pin P, said pin comprising a 75 round portion 25 and a relatively flat portion 26. At the juncture of these portions 25 and 26 a latch block 27 is formed, while directly above the latch block 27 the flattened portion 26 is provided upon its opposite 80 edges with guide blocks 28. The blocks 28 have a sliding fit within the grooves 24 of the walls 19 and 20 and thereby guide the coupling pin during its vertical movement, as will be understood. Arranged upon opposite sides of the coupling pin P are a pair 85 of gravity triggers T and T', each of which, as shown in Figure 7, comprises a body portion 29 having a substantially dove-tail groove 29a formed on one face thereof, 90 which latter, in turn, provides a hook 30, adjacent the upper end thereof, and a rib 30a adjacent the medial portion of the body. At the lower end of the body 29 the trigger is formed with a beveled surface 31 which 95 is inclined inwardly toward the coupling pin, as shown in Figure 5. As shown to advantage in Figure 5, the lower end of each trigger T or T' is curved in the form of an arc so that its lower end may be swung outwardly from the pin P without engaging the lower wall 21 of the housing A. The triggers T and T' are also capable of vertical movement within the housing A, and to guide the same during this movement and, 100 at the same time, to permit a swinging movement thereof, we provide pivot pins 32 adjacent the upper end thereof which work in the grooves 23.

As shown in Figure 5, the triggers T and 110 T' normally occupy substantially vertical positions under the action of gravity, and in

this position the ribs 30^a rest in grooves 27^a formed in the under side of the latch block 27, and because the lower ends of the triggers are resting upon the lower wall of the 5 housing A, the ribs 30^a engage the latch block 27 and thereby support the pin P in elevated position.

Should the triggers T and T' be swung outwardly about the pivot pins 32 as a center, 10 the ribs 30^a would disengage the latch block 27 and thereby permit the coupling pin P to gravitate to its lowermost position. In the lowermost position the circular portion 25 of the coupling pin P moves into the opening 18 15 and thereby spans the interior of the housing at the inner end of the mouth 17.

Referring now to Figures 2 and 4, K designates a coupling link which is adapted to be locked within the housing H by the coupling 20 pin P. The link K is provided with a shank 33 which is normally disposed within the draw head H', and is provided with an opening to receive a locking pin 34. The pin 34 extends through suitable openings formed 25 in the upper and lower walls of the draw head H' at the juncture of the compartments 16' and 17'. The inner end of the shank 33 is provided with a hook 35 which is connected with one end of a coiled contractile spring 30 36, the opposite end of such spring being connected to a pin 37. From this arrangement it will be seen that the coupling link K is supported for movement in a horizontal plane but is biased to a predetermined position 35 so that it is properly centered with relation to the mouth 17 by means of the spring 36.

With the parts of the coupler in the position shown in Figure 5, let it be assumed 40 that the cars are to be coupled. When either of the cars M or M' is moved toward the other, the projecting link K moves into the mouth 17 of the draw-head H and strikes the beveled surface 31 of the triggers T and T' 45 with sufficient impact to force the triggers outwardly thereby causing the lips 30^a to disengage the latch block 27. As soon as this occurs, the coupling pin P is free to gravitate to its lowermost position wherein the round- 50 ed portion 25 passes through the link K and into the opening 18 thereby securely locking the link within the draw-head and coupling the cars together. When uncoupling, it is necessary to partly lift the coupling pin until 55 it is withdrawn from the opening 18 and disengages the link K. The coupling pin is raised until the latch block engages the hooks 30 whereupon continued elevation causes the triggers to be raised so as to clear the link 60 and to swing inwardly back to the position shown in Figure 5. It will be obvious that with the triggers in this position the lips 30^a are again disposed in the path of movement

of the latch block so that when the coupling pin is released it descends until checked by 65 the lips thereby locking the pin in withdrawn position with respect to the opening 18 so as to again permit the withdrawal of the link K in effecting an uncoupling of the cars. 70

Although we have herein shown and described only one form of car coupling embodying our invention, it will be understood that various changes and modifications may be made herein without departing from the 75 spirit of the invention and spirit and scope of the appended claims.

We claim:

1. A car coupling comprising a draw head having an interior cavity and a tapered 80 mouth communicating with said cavity, a housing associated with the draw head and communicating with said mouth, grooves formed on the side walls of said housing, a coupling pin, guide blocks carried by said pin and working within certain of said grooves, a latch block fixed to said pin, a pair of triggers, pins adjacent the upper ends of the triggers and working within the remaining grooves, hooks formed on each of 85 said triggers and disposed upon opposite sides of said latch block, said triggers having beveled surfaces disposed within the mouth of said draw head, and a coupling link adapted to be inserted in said mouth 95 and to engage said beveled surfaces.

2. A car coupling comprising a draw-head, a pin movable vertically within the draw-head, a latch block fixed to said pin, a pair of triggers mounted for swinging movement 100 about horizontal axes, and a coupling link adapted to be inserted between said triggers to effect spreading thereof, said triggers being capable of occupying a position to maintain said coupling pin in releasing position 105 with respect to said coupling link and a releasing position to allow said coupling pin to move into locking position with respect to said coupling link.

3. A car coupling comprising a draw-head, 110 a coupling pin moving vertically through the draw-head, a latch block fixed to said pin, a pair of triggers pivoted within said draw-head to normally occupy a vertical position, lips formed on said triggers and engageable 115 with said block to support the pin in elevated position, hooks formed on the triggers and adapted to be engaged by the latch block for returning the triggers to vertical position, and a coupling link adapted to be inserted between said triggers for spreading the same to cause said lips to disengage said block. 120
